(57) **CLAIM**

The ornamental design for an instrument cluster, as shown and described.

DESCRIPTION

FIG. 1 is a front elevational view of an instrument cluster showing my new design; and,
FIG. 2 is a perspective view from one side, the perspective view from the opposite side being a mirror image thereof.
The broken line showings of the markings and indicia on the meters and dials, and the remainder of the front dash are for illustrative purposes only and form no part of the claimed design.
